[57] CLAIM

The ornamental design for a tire, as shown and described.

DESCRIPTION

FIG. 1 shows a perspective view of the present design, it being understood that the tread pattern repeats uniformly throughout the circumference of the tire;

FIG. 2 shows a front elevational view of the present design;

FIG. 3 shows a left elevational view of the present design, the opposite side elevational view being identical thereto; and,

FIG. 4 shows an enlarged fragmentary view of the tread design of FIG. 2.
